UNITED STATES PATENT OFFICE.

EZRA T. HAZELTINE, OF WARREN, PENNSYLVANIA.

BOOK-FOLDING MACHINE.

SPECIFICATION forming part of Letters Patent No. 369,599, dated September 6, 1887.

Application filed July 3, 1886. Serial No. 207,114. (No model.) Patented in England August 20, 1886, No. 10,678.

To all whom it may concern:

Be it known that I, EZRA T. HAZELTINE, a citizen of the United States, residing at Warren, in the county of Warren and State of Pennsylvania, have invented new and useful Improvements in Book-Folding Machines, (for which I have obtained a patent in Great Britain, No. 10,678, dated August 20, 1886,) of which the following is a specification.

This invention relates to improvements in the book-folding machine for which Letters Patent No. 345,506 were issued to myself and F. A. Weld July 13, 1886.

The object of my invention is to provide
15 novel means for moving the folded book into
engagement with the pressure-rollers between
which the book passes for pressing it along
the line of the fold made by the folding-blades.

The invention also has for its object to provide novel means for clamping the folded book to move it to the pressure-rollers without undue pressure being applied to the folding-blades, so that the knife can rise without liability of lifting the book.

25 The object of my invention I accomplish in the manner and by the means hereinafter described and claimed, reference being made to the accompanying drawings, in which—

Figure 1 is a side elevation of a book-fold-ing machine embodying my invention; Fig. 2, a top or plan view thereof, broken away at one side on the line $x-x$ of Fig. 1 to show the pressure - rollers and the clamping - jaws for moving the folded book into engagement therewith; Fig. 3, a vertical sectional view taken on the line $y-y$ of Fig. 1; Fig. 4, a detail perspective view of one pair of the clamping-jaws, showing also a portion of one of the upper book-folding blades; Fig. 5, a detail perspective view of one of the lower blades; Fig. 6, a sectional view of one of the clamp-operating cams, taken on the line $3-3$ of Fig. 7; Fig. 7, a side elevation of one of the cams, and Fig. 8 a detail sectional view of one of the clamp-ing-jaws.

43 *Eng. Jour.* In order to enable those skilled in the art to make and use my invention, I will now describe the same in detail, referring to the drawings, where—

50 The numeral 1 indicates a supporting framework; 2, the table having at each side a slot,

each of which has at its opposite edges a guide-plate, 3.

As in the machine forming the subject-matter of the application before referred to, an attendant sits at each side of the table and places one of the flattened-out books, back downward, upon the guide-plate 3 at the time the cross-head 4 is elevated. When the cross-head descends, the vertical blade 5, attached thereto, strikes the book along the folding-line and presses it down upon a vertical blade, 6, which is held in such position that its top edge is just below the book-back. The lower edge of the upper blade is chamfered to correspond to a groove in the top edge of the lower blade, and the two blades come sufficiently close for the upper blade to press the book at the folding-line into the groove of the lower blade to clamp or pinch the book. The motion of the two blades is thereafter coincident and downward to force the book between the guide-plates 3 sufficiently far to place the fold-line in a horizontal line passing between the pair of pressure-rollers 7, after which the blades separate, the upper one ascending, leaving the book folded between the guide-plates. It is now necessary to move the book in a horizontal plane to engage and pass between the pressure-rollers to press the book along the folded line and eject it from the machine into a suitable receptacle. To accomplish this I employ two jaws, 8, preferably of wood and capable of sliding back and forth in a rectilinear path on blocks 9, secured to a cross-plate, 10, fastened at its ends to the frame of the machine. These jaws at one end are curved into projecting points 11, so that such ends may pass between the rollers to or near their peripheral contact, and each jaw is slotted, as at 12, and provided with a metallic wear-plate, 12^a, Fig. 8, to receive the upper end of a lever, 13. These levers are mounted on independent pivot-pins 14, located in a frame, 15, having journals 16, by which it is swiveled in bearings 17 on a traverse, 18, extending across the machine.

Between the levers 13, above the swiveled frame, is a rod, 19, secured to one lever and passing through a hole in the other, said rod being encircled by a spiral or other spring, 20, the tendency of which is to separate the jaws, 100

as in Fig. 4. The lower ends of the levers have attached studs 21, engaging properly-shaped cam-grooves 22 in a cam, 23, fixed to a transverse shaft, 24, each of said grooves having within it an elevation, 25, Fig. 6, the construction being such that as the cams are rotated by the shaft 24 the elevations first spread the lower ends of the levers outward to swing them on their pivot-pins 14 to close the jaws 8 against the opposite sides of the folded line of the book, after which the levers are so acted upon by the walls of the cam-grooves as to cause them to swing the swiveled frame 15 in its bearings and advance the clamping-jaws toward the pressing-rollers 7, so that the points 11 deliver the book directly to the peripheral contact-point of the rollers, which grip the book, and immediately thereupon the jaws are, by the cams, released and restored to their normal position to clamp and advance another book.

In order to prevent the clamping action of the jaws from exerting undue pressure on the upper folding-blade while it is between the folded book, which would interfere with the withdrawal of the blade and be liable to lift the book, I provide the acting face of one of the jaws with a projection, 26, which may consist of a staple driven into the jaws, if the latter are of wood, which is preferable. This projection is in line, vertically taken, with a notch, 27, in the lower edge of the upper blade, so that the projection presses on the folded book through such notch and to a large extent prevents the acting faces of the jaws from unduly clamping the book upon the opposite sides of the blade, thereby permitting the latter to rise without disturbing the folded book.

There are three shafts, 24, 28, and 29, extending across the machine-frame, the shaft 28 having a pulley, 30, for the driving-belt, and also a pinion, 31, engaging a spur-wheel, 32, on the shaft 24, which spur-wheel meshes into a smaller spur-wheel, 33, on the shaft 29, the latter having a bevel-wheel, 34, engaging a bevel-wheel, 35, on the vertical shaft of one of the pressure-rollers, which shaft is geared with the other pressure-roller shaft by gear-wheels 36 38, whereby the pressure-rollers are rotated.

The cross-head 4 is secured to a vertical rod, 4^a, adapted to slide up and down in suitable bearings, and is operated by a cam, 37, on the shaft 24. These features, their mode of operation, and the means for operating the lower

blade, 6, by cams and springs, are substantially identical with those forming the subject-matter of the aforesaid application for Letters Patent, and therefore a further detailed explanation is not deemed essential.

Having thus described my invention, what I claim is—

1. The combination, with the book-folding blades and the pressure-rollers, of opening and closing and laterally-movable clamping-jaws for moving the folded book into engagement with the pressure-rollers, substantially as described.

2. The combination, with the book-folding blades and the pressure-rollers, of jaws moving first toward each and then together moving laterally for clamping the folded book and delivering it to the pressure-rollers, and means, substantially as described, for so operating the jaws.

3. The combination, with the book-folding blades and the pressure-rollers, of two clamping-jaws, a swiveled frame, two levers pivoted in the swiveled frame, and means, substantially as described, for first operating the levers to clamp the jaws on the folded book, and thence advance the jaws to deliver the book to the pressure-rollers, substantially as described.

4. The combination, with the pressure-rollers for pressing a folded book along its folded line, of opening and closing and laterally-movable jaws for clamping the folded book and delivering it to the pressure rollers, substantially as described.

5. The combination, with the folding-blade having a notch, of the opening and closing and laterally-moving jaws, one of which is provided with a projection on its acting face arranged in line with the notch in the blade, substantially as and for the purpose described.

6. The combination, with the pressure-rollers for pressing a folded book, of the sliding jaws, the swiveled frame, the levers pivoted in the swiveled frame and connected with the jaws, and the cam acting on the lower ends of the levers for moving the jaws to and from each other, and also to and from the pressure-rollers, substantially as described.

In testimony whereof I affix my signature in presence of two witnesses.

EZRA T. HAZELTINE.
